UNITED STATES PATENT OFFICE.

GEORGE JAMES, OF BOSTON, MASSACHUSETTS.

METHOD OF AND MEANS FOR CUTTING HEEL-LIFTS.

SPECIFICATION forming part of Letters Patent No. 361,065, dated April 12, 1887.

Application filed October 30, 1886. Serial No. 217,592. (No model.)

To all whom it may concern:

Be it known that I, GEORGE JAMES, of Boston, in the county of Suffolk and State of Massachusetts, have invented certain new and useful Improvements in Methods of and Means for Cutting Out Heel-Lifts, of which the following is a specification.

This invention relates to the mode of and means for cutting out heel-lifts for boots and 10 shoes, and has for its object to provide an improved process of gaging or governing the feed of the material being operated upon in order to secure exactness in position of the same in regard to the cutting-die, so as to reduce waste 15 of leather to the minimum and avoid the cutting out of imperfect lifts, and to construct improved means for carrying out this process.

To these ends my invention consists in the improvements, which I will now proceed to describe, so that others skilled in the art may make and use or practice the same, reference being had to the accompanying drawings, and to the letters of reference marked thereon, forming a part of this specification, and the 25 invention being particularly pointed out and distinctly claimed at the end of the description of its construction and manner of use.

Of the drawings, Figure 1 represents an end view of a machine embodying my improved 30 means, parts being broken away. Fig. 2 is a front elevation of the same. Fig. 3 is a top plan view of the machine, the cross-head and some of its associated parts being broken away. Figs. 4 and 5 are diagrams illustrating the 35 steps pursued in my improved mode of procedure.

Similar letters of reference indicate similar parts in all of the views.

a represents the frame, in which is suitably 40 journaled the main shaft *b*, having affixed thereto a fly or balance wheel, *c*, and provided with crank mechanism *d*, connected by a pitman, *e*, with a treadle, *f*.

g represents a cross head or beam attached 45 to one end of arms *h*, pivoted at their opposite ends to the upper part of the frame. The main shaft carries two disks, *i i*, one at each end, to which are eccentrically connected the lower ends of rods *j j*, the upper ends of which are 50 pivoted to arms *h*.

k indicates the bed of the machine, provided

with an adjustable side or edge guide, *l*, of common construction.

m represents a die having the form of the heel-lift to be cut, which die is secured to the 55 cross head or beam *g* in the usual manner; and *n* represents a stabber or marker, also secured to the cross head or beam *g*. Said stabber or marker is sharpened at its lower end, and so positioned with respect to the cutting-die *m* as 60 that when a series of heels is being cut from a piece or strip of leather—as, for example, a strip capable of having two series of lifts cut therefrom, as represented in Figs. 4 and 5—it will stab or indent the material at a point opposite 65 the rounded portion of the lift cut out, and what would be midway between the sides of such lift if it were extended into the strip or side of leather, so that when the next series of lifts are cut for the material in such manner that 70 their rounded ends will fall between the like ends of the previously-cut lifts, said indentations or stabs will come between the lifts, and preferably in the cut-away or waste material, as shown particularly in Figs. 4 and 5, in which 75 *a' a'* represent heel-lifts cut from a strip of material; *b' b'*, the stabs or indentations made in the material in cutting out such lifts; and *c' c'*, the points at which the next series of lifts will be cut from the material.

It is obvious that the stabber or marker may be so positioned on the cross-head as to stab or mark the material at a point which will fall on the line of a cut subsequently made by the die *m*, the object being to not mark or 85 mar the material at a point falling within the lines of a heel-lift that may be cut out.

o represents two vertically-arranged rods, one on each side of the machine, the lower ends of which rest on the periphery of the 90 disks *i*, provided at a proper point with a cam-swell, *p*, as shown in Fig. 1. Said rods *o* are pivotally connected at their upper ends each with the outer end of a short arm, *q*, rigidly affixed at its other end to a rock-shaft, *r*, journaled in suitable bearings on the edge of the 95 bed, and provided at its inner end with an angular arm, *s*, from each of which rock-shafts depends a finger, *t t'*.

The operation of the machine is as follows: 100 A piece of leather, preferably a strip of proper width to have two series of heel-lifts cut there-

from, as represented in Figs. 4 and 5, is placed upon the bed *k*, and the side or edge guide, *l*, adjusted so as to bring the edge of the material in proper position with respect to the cutter *m*. The machine is operated by the treadle *f* to bring the cutter *m* upon the material and cut or die out a heel-lift, *a'*. The stabber *n* at the same time operates to stab or mark the strip by independent marks, as at *b'*, which is 10 at a point precisely midway between the series of lifts *c'* next to be cut after the series *a'* have been died out. As the cutter and stabber are raised the cam-swell *p* on the disk *i* passes under the lower end of rod *o*, which operates 15 in a way that will be readily understood to raise finger *t*, and allow the strip of material to be moved along thereunder to a point where said finger *t* will drop into the stab, indentation, or mark made by the stabber *n*, which 20 will bring the material in exact position to have the cutter *m* in its next operation die out a lift, *a'*, with the least possible waste, making another stab or mark, *b'*, as before. After the 25 series of lifts *a'* have been cut or died out, the strip is reversed in position so as to bring its other edge against the guide *l*, and another series of lifts, *c'*, are cut from the other side of the strip so their rounded ends will fall between the rounded ends of the previously cut series, as 30 shown, the guide or gage finger *t'* at the other side of the bed operating in the marks or stabs *b'* as the material is fed along, to secure exactness of position of the strip or piece with respect to the cutter *m*. 35 It will be understood that in cutting out the first series of lifts, *a'*, from the strip guide-finger *t* operates without effect along the line from which such lifts are being cut, and that when the strip is reversed both the stabber *n* 40 and the guide-finger *t* operate without effect along the line from which said lifts *a'* had been cut, the stabs or marks *b'* now coming into position, so that guide-finger *t'* at the side of the machine opposite guide-finger *t* will operate in said stabs or marks. In other words, 45 in a strip of material like that represented in Fig. 4, from which two series of lifts are cut, but a single line or series of stabs, *b'*, are made, and which is accomplished when the first series 50 of lifts *a'* are being cut out, said stabs or marks serving as a guide for both series—that is to say, when the first lift *a'* was cut from the material the first stab *b'* was made therein. The material was then fed along to guide-finger *t*, 55 (guide-finger *t'* operating without effect,) and the next lift was cut, and another stab or mark was made for the next lift. Upon reversing the strip guide-finger *t'* falls in the marks or stabs *b'*, and finger *t* and stabber *n* operate 60 without effect along the line from which the series of lifts *a'* were cut from the strips.

By the method and means described absolute precision of position of the piece or strip with respect to the cutter is secured and unnecessary waste of material and imperfectly cut lifts avoided.

It is not essential to my method that the pre-

cise means shown for stabbing or marking the strip or material should be employed, or that it should be operated in the exact manner explained, or that the strip or material should be stabbed at the precise point indicated, the essential feature with respect to this step being that the material shall be stabbed or marked at some point having each time the same relationship as to position to the die or cutter, and so that a gage of any desirable form or construction, and operated in any suitable way, may be enabled to guide the material to exactly proper position at each successive operation, and thus avoid waste of material. The means herein shown and described are, however, the best known to me for carrying out my improved method.

What I claim is—

1. The art of producing heel-lifts, which consists in cutting out a lift and simultaneously marking at one side of the lift cut out, preferably at a point half the width of the lift to the rear of the front side of the lift so cut out, and then feeding the material forward until the mark previously made coincides with a point which is half the width of the lift in advance of the front edge of the lift die or punch, and repeating these steps, all substantially as and for the purposes hereinbefore set forth.

2. The improvement in the art of producing heel-lifts, which consists in cutting out a lift and simultaneously marking at one side of the lift cut out, substantially at a point opposite the rounded portion of the next lift to be cut out, and what would be substantially midway between the sides of such last-mentioned lift if they were extended into the strip or "side" of leather, then feeding the material forward the distance corresponding exactly to the width of a lift, and setting a gage so as to register with the mark previously made, and cutting out another lift and marking the material, as before, then feeding the material forward so that the mark last made will register with the gage, and again cutting out a lift and marking the material, as before, and repeating these operations to complete the cutting out of a line or series of lifts, then cutting out a lift of another line or series of lifts in such manner that its rounded end will fall between the like ends of two previously-cut lifts of the preceding series, and arranging a gage to correspond with one of the marks previously made in the material, and feeding the latter forward so that the next mark in line, made as before explained, will range or register with said gage, and cutting out another lift, and repeating these operations to cut out a second series of lifts, as set forth.

3. In an apparatus for cutting out heel-lifts, a cross-head, a cutting-die, and a stabber or marker, *n*, affixed to the cross-head, the latter outside of the former, and mechanism for operating the same, combined, arranged, and operating substantially as hereinbefore set forth.

4. In an apparatus for cutting out heel-lifts, a cross-head, a cutting-die, a stabber or marker, *n*, thereon, the bed of the machine, and a guide or gage finger thereon, and mechanism 5 for operating the same, combined, arranged, and operating substantially as set forth.

In testimony whereof I have signed my name

to this specification, in the presence of two subscribing witnesses, this 22d day of October, 1886.

GEORGE JAMES.
